35—

UNITED STATES PATENT OFFICE.

EDWARD A. BASKERVILLE, OF OMAHA, NEBRASKA.

BOOKKEEPING DEVICE.

Application filed January 3, 1925. Serial No. 373.

This invention relates to new and useful improvements in bookkeeping devices particularly adapted for use in making double entries on a journal sheet, and more particularly relates to such a device having a movable guide means which is cooperable with the journal sheet to accurately locate thereon the debit and credit entries of each transaction.

10 A further object of the invention is to provide a bookkeeping device having an independently movable guide curtain arranged therein which is provided with pairs of elongated apertures through which the debit and credit entries of each transaction must be recorded on a columnar journal sheet positioned therebeneath, after such entry has been properly classified by means of an index arranged on one side of the apparatus, thereby eliminating the prevalent danger of some of the entries being inaccurately made upon the journal sheet.

15 A further object is to provide such a device having an index finger or pointer operatively connected to the movable curtain thereof, so that when the curtain is actuated to selectively bring the index finger into registration with the selected classification on the index, a pair of the elongated openings or slots in the curtain will appear through an opening in the top of the device so that the debit and credit entry of the transaction may be made therethrough in the proper columns on the journal sheet.

20 30 35 A further object is to provide a guide curtain adaptable for use in accurately locating on a columnar journal, double entries such as the debit and credit of a transaction, and also having means whereby a profit and loss statement may readily and quickly be computed at any time with a minimum amount of labor.

40 45 50 The particular object of the invention therefore, is to provide an improved bookkeeping device of simple and inexpensive construction, by the use of which an inexperienced person of ordinary intelligence may quickly and accurately record on a journal sheet, the debit and credit entries of each transaction, it being understood that the device is particularly designed for use in connection with the well-known double entry system of bookkeeping.

Other objects of the invention will more

fully appear from the following description 55 and the accompanying drawings and will be pointed out in the annexed claims.

In the drawings there has been disclosed a structure designed to carry out the objects of the invention but it is to be understood that the invention is not confined to the exact features shown as various changes may be made within the scope of the claims which follow.

55 In the drawings: 65 Figure 1 is a plan view of a bookkeeping register showing the invention applied thereto;

Figure 2 is a cross-sectional view on the line 2—2 of Figure 1, showing the preferred 70 manner of arranging the guide curtain over the journal sheet;

Figure 3 is a horizontal sectional view on the line 3—3 of Figure 2, showing the arrangement of the guide slots in the curtain 75 through which the entries are made on the journal sheet;

Figure 4 is an end elevation of the register shown in Figure 1;

Figure 5 is an enlarged detail sectional 80 view on the line 5—5 of Figure 4 showing a method of securing the index finger to the movable guide curtain, and also showing how the index finger is preferably hinged so that it may readily be swung to 85 the position shown in dotted lines when the cover of the device is opened or raised;

Figure 6 is an enlarged detail view of a portion of the journal sheet with the guide 90 curtain arranged thereover; and

Figure 7 is an enlarged view of a portion of the journal sheet showing how it is preferably ruled, and a portion thereof divided into double columns to receive the debit and credit entries made thereon through the slots 95 in the guide curtain.

In the selected embodiment of the invention here shown for purposes of disclosure, there is illustrated a bookkeeping device for register preferably comprising a metallic 100 casing having the opposed side walls 11 and 12 and the front and rear walls 13 and 14, respectively, as shown in Figures 1 and 3.

An important feature in this invention resides in the novel means provided for locating the debit and credit entries on a journal sheet, such as is commonly employed in what is known as the "double entry system"

of bookkeeping. Such means preferably consists in the provision of a flexible guide member or curtain 15 having a plurality of elongated apertures 16 provided therein which are arranged in pairs transversely of the curtain. This curtain is placed over the journal sheet 17 and the debit and credit entries are made through the apertures 16 on the journal, the apertures functioning to accurately locate the entries in their respective columns on the journal.

In the form of bookkeeping device shown in the accompanying drawings, the journal sheet 17 is preferably mounted upon a pair 15 of rolls 18 and 19 mounted upon shaft 20 journaled in suitable bearings provided in the side walls of the casing. In preparing the device for use the journal sheet is preferably mounted upon the lower roll 19 and the free end thereof is then passed upwardly over an inclined supporting plate 21 back to the roll 18 at the rear of the register, to which roll it is demountably secured by suitable means not shown. One end of each shaft 20 preferably outwardly projects through the wall 11 of the casing, as shown in Figures 1 and 3, and a hand grip or knob 22 is suitably secured to the end of each shaft whereby the rolls 18 and 19 may be conveniently rotated in either direction to change the position of the journal sheet on the supporting plate 21. In the drawings, the journal sheet is shown as being in the form of a long sheet, which, before being used, is mounted on the roll 19 and is fed therefrom over the supporting plate 21 to the receiving roll 18 as hereinbefore described. If desired, however, the journal sheet may be made in the form of an endless belt; that is, one end will be passed over the supporting plate 21 and around the two rolls and the two ends secured together so that when either of the hand grips 22 are rotated, the journal sheet will be operated as an endless belt. When thus used, the joint between the two ends will be opened when the journal sheet has been filled with the various entries, after which it may readily be removed from the rolls and a new journal sheet substituted therefor. The bearings in which the shaft 20 is mounted are preferably of such construction as to frictionally prevent the trailing roll from overrunning when the position of the journal sheet is being shifted, thereby causing the portion of the journal between the rolls to be continuously held taut or under a slight tension.

As hereinbefore stated, and as particularly shown in Figures 2 and 3, the feature of this invention resides in the guide member or curtain employed in conjunction with the journal sheet to accurately locate the debit and credit entries upon a predetermined portion thereof. Referring to Figure 2, it will

be seen that the guide curtain 15 is preferably mounted upon a pair of rolls 23 and 24 which are similarly mounted upon shafts 25 journaled in the bearings provided in the side walls of the casing. These bearings 70 are similarly adapted to prevent the shafts 25, and therefore the rolls 23 and 24 from overrunning when the position of the guide member is changed. Each of these shafts also has one end outwardly projecting 75 through the side wall 11 of the casing to receive a hand grip or knob 26 by means of which the shafts 25 and therefore, the rolls 24 and 23, may conveniently be rotated to shift the position of the curtain with respect 80 to the journal sheet positioned therebeneath. A guide rod 27 is preferably provided adjacent the rear end of the casing to guide the curtain 15 over the receiving roll 18 upon which one end of the journal sheet is 85 wound.

The top of the casing is preferably closed by means of an inclined cover 28 pivotally connected by hinges 29 to the upper horizontal wall 31, provided adjacent the rear 90 wall 14 of the casing. A rectangular opening 32 is preferably provided on one side of the cover through which a portion of the journal sheet may be seen as shown in Figure 1. Through this opening, each transaction will be made on the journal sheet directly above the lower marginal edge 33 of the opening, as shown in the above-mentioned figure. The marginal edges of the rectangular opening 32 are preferably downwardly bent or inclined, as shown in Figure 2, so that when the cover is closed and in operative position, the marginal edges of the opening will be positioned comparatively close to the upper surface of the journal sheet. An elongated opening or slot 34 is also provided in the cover and extends from the opening 32 transversely across the cover as shown in Figure 1. Through the opening 34, the debit and credit entries are 100 made through the elongated apertures 16 upon the journal sheet, positioned therebeneath. The preferred form of journal sheet employed in conjunction with this novel guide curtain is preferably ruled and divided into columns as shown in Figure 7. As here shown, the left hand margin of the sheet is preferably provided with a narrow space 35 for the date of entry, and a relatively wider space 36 in which each transaction is recorded. The balance of the sheet is preferably divided into suitable double columns which bear such headings or classifications as Cash, Accounts due us, Merchandise, Interest and discounts, etc. A Loss and 115 Gain column is preferably provided on the right hand side of the journal sheet. The journal sheet is also provided with a transverse space 37 in which the sum total of the debits and credits, entered in each col- 120 130

umn, may be recorded. A similar transverse space 38 is also preferably provided in which the resulting grand totals of all accounts may be extended, after a loss and gain statement 5 has been computed, as will hereinafter be described.

The means provided for predetermining the particular pair of slots in the curtain to be used in entering a given transaction, preferably resides in the provision of a suitable index 39 which is preferably mounted on one side of the cover opposite the rectangular opening 32. An index finger or pointer 41 is pivotally mounted on an angular bracket 42 which is suitably secured to one edge of the curtain 15 by such means as the rivets 43. A spring member 44 is secured to the upright portion of the bracket 42 and has its flexible end bearing against the hub of the pointer 41, so as to frictionally retain the pointer in its adjusted positions, as indicated in full lines and dotted lines in Figure 5. The upper end of the spring member 44 also functions as a stop for limiting the downward movement of the pointer to prevent it from contacting with the upper surface of the cover or index. (See Figure 1.) An elongated aperture or slot 45 is provided in the side wall 12 of the case to provide clearance for the bracket 42 when the curtain is actuated by manipulation of the hand grips 26.

The pointer 41 is preferably pivotally mounted on the bracket 42 so that it may 35 be upwardly swung to the dotted line position in Figure 5 when the cover 28 of the register is raised to gain access to the interior of the device.

When an entry is to be made on the 40 journal sheet, the description of the transaction will first be recorded on the left hand side of the journal through the opening 32 in the cover and above the lower marginal edge 33 thereof, such edge functioning as a 45 guide for the operator in recording the transaction on the journal sheet. The operator will then determine by reference to the index under which classification on the index the amount of the transaction is to be recorded. After having determined the 50 proper classification, which may readily be accomplished by any one though unfamiliar with bookkeeping, the pointer 41 is moved to the selected classification by means of the 55 hand grips or knobs 26. After the pointer has thus been moved into registration with the selected classification, which is shown in Figure 1 as being "Purchased merchandise by cash", a pair of slots 16 will appear 60 through the elongated opening 34 in the cover, and through these openings the amount of the transaction will be made on the journal sheet thereby accurately locating the amount of the debit and credits for 65 such entry. For illustration, it will be seen

by referring to Figures 1 and 7 that the last transaction recorded on the left hand side of the journal sheet was a purchase of merchandise for cash amounting to \$120. After the above transaction has been recorded on the left hand side of the journal sheet, as shown in Figure 1, the index finger 41 is moved to the uppermost heading on the index which, in this particular case, refers to the purchase of merchandise by cash. When the pointer has thus been positioned the slots 16 in the curtain, appearing through the elongated opening 34 of the cover, will be in alignment with the Cash and Merchandise columns on the journal sheet, so that when the amount of the entry has been made through the slots 16 upon the journal sheet they will be located in their proper columns as shown in Figure 7. Referring to this figure, it will be noted that the entry has been made on the credit side of the Cash column and on the debit side of the Merchandise column, thereby indicating that the amount of such transaction has been paid out and that merchandise equal to the amount paid out has been received. Thus it will be seen that as each transaction is made through the rectangular opening 34 in the cover on the journal sheet therebeneath, it is only necessary for the operator to determine on the index, the proper classification of the transaction, after which the pointer 41 will be moved to the selected classification and the amount of such transaction be made through the slots appearing in the curtain through the elongated opening 34 of the cover thereby accurately locating such amounts in their proper columns on the journal.

By the use of this simple device, therefore, it will be impossible for an operator to inaccurately locate the debit and credit entries on the journal sheet if the index pointer 41 is moved to the proper classification on the index for each transaction.

Another important feature of this invention resides in the novel means provided on the guide curtain 15 whereby a profit and loss statement may readily and quickly be computed at any time with a minimum amount of labor, and whereby such a statement may readily and accurately be computed by one unfamiliar with the art of bookkeeping.

To compute a profit and loss statement from any journal, when employing the double-entry system of bookkeeping, it is well-known to those familiar with the art, that only certain amounts are utilized, such amounts usually being the totals of the debits and credits of each of the following columns, merchandise bought and sold, interest and discount, and the general expense column. After the debits and credits of these columns have been totaled, the amounts

125

130

are usually entered in the transverse space 37 of the journal, as shown in Figure 7. However, before the profit and loss statement is computed, the debit and credit amounts of each of the above mentioned columns are preferably transposed so that the journal can be balanced, after which such amounts are extended to the loss and gain column, preferably at the extreme right 10 hand margin of the journal. In order to balance the debit and credit amounts, they must be transposed from their respective positions in the space 37 to that shown on the lower portion of the journal between 15 the transverse spaces 37 and 38, in which positions, it will be noted that the debits have been transposed to the credit side of each column, and the credits to the debit side of each column. The debit and credit 20 amounts are then extended to the loss and gain column, as above mentioned, after which the profit and loss statement may readily and quickly be computed.

At present, the above operation is executed without the aid of a guide other than the columns into which the amounts are to be entered, and extreme care must, therefore, be exercised on the part of the book-keeper or clerk in making such transpositions, in order to eliminate the possible danger of inaccurately locating the amounts in their proper columns on the journal.

It is therefore, desirable that means be provided whereby it will be impossible to inaccurately enter the debit and credit amounts on the journal in making the above transpositions, so that a novice or inexperienced person may readily and accurately transpose the debit and credit amounts and extend 40 them to the loss and gain column and thereafter compute the profit and loss statement, the only requirement being that no errors be made in the figures of the various amounts in transposing them.

45 The means provided on the guide curtain to thus facilitate the computing of a profit and loss statement from the journal in a minimum amount of time, and without the prevalent danger of erring, preferably resides in the provision of a group of apertures in the lower portion of the curtain adjacent the lowermost pair of slots 16, through which the debit and credit entries are made on the journal. As shown in Figures 3 and 6, a series of slots 46, 47, 48, 49 and 51 are arranged in longitudinal alinement in the lower central portion of the curtain, and as particularly shown in Figure 6, are also arranged so as to be in registration with the debit and credit amounts of the merchandise, interest and discount and general expense columns.

Each of the above slots is connected with a pair of complementary slots by suitable 65 means, inscribed or marked on the curtain,

whereby the debit and credit amounts may first be accurately transposed for balancing the journal, and thereafter be extended to the loss and gain column, preparatory to computing the profit and loss statement. As 70 shown in Figure 6, the slot 46 has a leader or guide line 52 connecting it with a slot 53 which is connected with a similar slot 54 by means of a leader 55, and the slot 47 is connected with a pair of slots 56 and 57 by 75 means of leaders 58 and 59. Similarly, the slot 48 is connected with slots 61 and 62 by leaders 63, and 64; the slot 49 with slots 65 and 66 by leaders 67 and 68, and the slot 51 with slots 69 and 71 by means of similar 80 leaders 72 and 73. A pair of slots 74 and 75 are also provided in the curtain beneath the above group of slots. The slot 74 is preferably located beneath the slot 56 in alinement with the debit side of the merchandise column. A leader 76 connects the slot 74 with the slot 75 so that the amount of the inventory may be entered in the slot 74 and then accurately extended to its proper position in the loss and gain column, as shown in 90 Figure 6.

Thus, by the employment of the above-described group of slots, it will readily be seen and understood that after the debit and credit entries in the merchandise, interest 95 and discount and general expense columns have been totaled in the space 37 on the journal, and the curtain 15 has been positioned thereover as shown in Figure 6, such amounts may readily and quickly be transposed to balance the journal and thereafter extended to the loss and gain columns. In transposing the amounts to balance the journal the operator will be guided by the guide lines or leaders connecting the sets of complementary slots, as above-described, thereby eliminating any possible danger of making an error in locating the amounts.

After the amounts have been extended to the loss and gain column, the curtain may 110 be removed by lifting it off the journal after which the extended amounts may be totaled, as shown in Figure 7. The difference between the two totals thus obtained will prove to the operator or merchant whether a profit 115 or loss has been made at the close of a business period.

Thus, by the provision of the above-described group of slots on the guide curtain 120 it will readily be seen that an inexperienced person or novice may readily and accurately balance the journal and also compute a profit and loss statement in a minimum amount of time and without the possible danger of inaccurately locating the amounts 125 in transposing and extending them. The grouping of the slots may be varied in numerous ways without departing from the invention.

Having thus described my invention, what 130

I claim as new and desire to secure by Letters Patent, is:

1. In a bookkeeping device for making entries on a journal including a journal sheet; an apertured guide curtain therefore, the apertures in said curtain being arranged in pairs so that double entries may be made on the journal sheet therethrough, an index, comprising a list of classifications covering transactions to be made on the journal sheet, an index finger or pointer operatively connected to the curtain, and means for selectively moving the index finger to a predetermined classification on the index and simultaneously moving the curtain to bring a pair of its guide apertures to a corresponding position over the journal so that entries made therethrough will be accurately located upon the journal sheet.
2. In a bookkeeping device for making debit and credit entries in a journal including a journal sheet; a movable flexible guide member having means thereon for accurately locating double entries on said journal, and said member also having means including dual sets of apertures therein through which may be made on the journal sheet an entry of journal totals whereby a profit and loss statement may readily be taken at any time with a minimum amount of labor.
3. In a bookkeeping device for making entries on a journal including a journal sheet; a flexible guide member having a plurality of guide slots provided therein through which debit and credit entries may be accurately located on the journal sheet, means for selectively moving the guide member to a predetermined position over the journal sheet, and said guide member also having means including dual sets of apertures provided therein through which may be made an entry on the journal sheet and transfer of journal totals whereby a profit and loss statement may readily and quickly be computed at any time.
4. In a bookkeeping device for making double entries including a journal sheet, and means for supporting the sheet; a flexible guide-member movably arranged over and disposed adjacent to the upper surface of the journal sheet, said flexible member having elongated apertures arranged in pairs through which debit and credit entries may be made on the journal sheet, and means for independently actuating the journal sheet and also the flexible guide member in either direction.
5. In a bookkeeping device for making double entries including a journal sheet; the combination of a casing, rolls to receive a journal sheet, a flexible guide member also mounted on rolls in the casing, said guide member having a plurality of elongated apertures the positions of which determine debit and credit entry of amounts to be re-
- corded on the journal, said apertures being arranged in pairs transversely of the guide member, and a cover for the casing having an elongated opening therein through which entries may be made through the apertures in the guide member and upon the journal sheet positioned therebeneath.
6. In a bookkeeping device for making double entries including a journal sheet, the combination of a casing, rolls mounted therein to receive a journal sheet, means for supporting the tensioned portion of the journal sheet between the rolls, a flexible guide curtain mounted over the journal sheet and having its ends demountably secured to a pair of rolls, said curtain having a plurality of slots through which debit and credit entries may be made on the journal sheet, a cover for the casing having an opening through which a record of each transaction may be recorded on one side of the journal sheet, said cover also having a transverse elongated opening exposing a portion of the guide curtain, an index on the cover, an index finger operatively connected to said curtain means for selectively moving said index finger into registration with a predetermined heading on the index, thereby causing a pair of the slots in the curtain to be moved into alinement with the elongated opening in the cover so that debit and credit entries may be made therethrough and accurately located on the journal sheet, positioned therebeneath.
7. In a bookkeeping device for making double entries including a movable journal sheet; the combination of a movably mounted member having a plurality of spaced apertures therein through which entries may be made upon said journal sheet, and means for independently actuating the journal sheet and the apertured member.
8. In a bookkeeping device for making double entries in a journal having headings and a debit column and a credit column under each heading; a member movably mounted adjacent the journal and having a plurality of pairs of apertures, the apertures of each pair being adapted to expose a portion of a predetermined debit and a predetermined credit column on said journal, a slotted cover for said member and journal and means for moving said member to present a pair of apertures opposite the slot whereby a specified area of said journal columns is thereby defined, an index to said pairs of apertures on the cover and a pointer cooperable with said index and connected to said movable member whereby entries may be selectively made.
9. In a bookkeeping device for making double entries including a journal sheet; an apertured flexible guide curtain movably arranged thereover for the purpose of accurately locating entries to be made upon

said journal sheet, and means for moving said guide curtain.

10. In a bookkeeping device for making double entries including a journal sheet; 5 an apertured guide curtain movably arranged thereover, the apertures in said guide curtain being arranged in pairs for the purpose of making debit and credit entries therethrough on the journal sheet, and 10 means for selectively and independently actuating said curtain to move a pair of the apertures therein to a selected position over said journal sheet, thereby to accurately locate thereon the entries to be made.
15. 11. In a bookkeeping device for making double entries including a member having headings and a debit column and a credit column under each heading; a movable member having a plurality of pairs of apertures, the apertures of each pair being disposed to expose a portion of a selected debit

and a selected credit column on the first mentioned member.

12. In a bookkeeping device for making double entries in a journal entry member 25 having headings and a debit column and a credit column under each heading; a member movably mounted adjacent the journal entry member and having a plurality of pairs of apertures, the apertures of each 30 pair being disposed to expose a portion of a selected debit and a selected credit column on said journal entry member, a slotted cover for said movable member and journal entry member, and means for moving one member to present a pair of apertures opposite the slot whereby a specified area of said journal entry columns is thereby defined.

In witness whereof, I have hereunto set my hand this 29th day of December, 1924.

EDWARD A. BASKERVILLE.
